(57) **CLAIM**

We claim the ornamental design for a hand-held electronic device, as shown and described.

DESCRIPTION

FIG. 1 is a back perspective view of a hand-held electronic device;

FIG. 2 is a front perspective view of a hand-held electronic device;

FIG. 3 is a front plan view of a hand-held electronic device;

FIG. 4 is a back plan view of a hand-held electronic device;

FIG. 5 is a right plan view of a hand-held electronic device;

FIG. 6 is a left plan view of a hand-held electronic device;

FIG. 7 is a top plan view thereof; and,

FIG. 8 is a bottom plan view thereof.

The broken lines in the drawings illustrate unclaimed portions of the hand-held electronic device and form no part of the claimed design.
